PROTECTIVE CONTROL CIRCUIT AND APPARATUS

Joseph R. Zwickl, Philadelphia, Pa., assignor to Baldwin-Southwark Corporation, a corporation of Delaware

Application September 27, 1935, Serial No. 42,492

9 Claims. (Cl. 62—4)

This invention relates generally to air conditioning apparatus of the type employing a compression refrigerating system having an air-cooled condenser and the invention relates more particularly to an improved control circuit for the compressor and the condenser blower motor.

It is an object of my invention to provide in air conditioning apparatus an improved control system in which the elements are so arranged in combination with each other that the compressor motor is effectively disconnected in the event of partial failure of the compressor circuit, such as failure of one phase of a multi-phase circuit, and is also protected against abnormal loading which may be caused by improper condenser operation such as failure of the blower motor. It is a further object to accomplish the foregoing desirable object in a manner which is economical in construction, maintenance and operation, and yet is simple, positive and fool-proof whereby the apparatus may be placed in the hands of an inexperienced user with utmost safety to the apparatus and to the user in operating the same.

Other objects and advantages will be more apparent to those skilled in the art from the following description of the following drawings in which:

Fig. 1 is a diagrammatic outline of a refrigerating system in which my improved control may be embodied;

Fig. 2 is a wiring diagram showing my improved circuit and control for a single phase compressor motor;

Fig. 3 is a modification of Fig. 2 but showing the application of my invention to a three-phase compressor motor;

Fig. 4 is a wiring diagram of a modification for a two-phase compressor motor;

Fig. 5 is a wiring diagram for a single phase compressor similar to that shown in Fig. 2 but embodying a modified form of pilot circuit control.

In the particular embodiments of the invention which are disclosed herein merely for the purpose of illustrating certain specific forms among possible others that the invention might take in practice, I have shown in Fig. 1 a diagrammatic arrangement of a refrigerating system having a compressor 1, a condenser 2 and evaporator 3 all suitably connected in any usual manner to provide a compressor-condenser-evaporator circuit. The condenser is preferably cooled by outside air circulated by a blower 4 through a passage 5. Room air is circulated by

a blower 6 through a passage 7. It is of course understood that the apparatus as described is embodied in a unit suitable for location in a room or other enclosure as may be desired, although the invention is applicable to any refrigerating system where the component elements thereof are located for remote use. The blowers 4 and 6 are suitably driven by power means specifically shown as a common motor 11. The arrangement of the main circuits for the blower and compressor motors and the pilot circuit therefor will be more readily understood by the following description of their operation.

To start the refrigerating unit, switch 10, Fig. 2, is closed thereby supplying current to fan motor 11 from the main lines 12 and energizing the primary coil of a transformer 13. Upon closure of a compressor switch 14, a pilot circuit is energized from the secondary coil 15 of transformer 13 provided that a thermostat or other auxiliary control device diagrammatically indicated at 16 is closed. The closure of the pilot circuit causes a solenoid 17 therein to be energized and thus close main contactors 18 which supply current from main line 12 to compressor motor 19. Any suitable type of overload relays may be used to control the pilot circuit in accordance with the main compressor current, one such relay being diagrammatically indicated as including current coils 20 for operating switches 21 in the pilot circuit.

From the foregoing disclosure it is seen that if the fan motor circuit is opened or fails for any reason, such as by burning out of the fan motor or the blowing out of any usual fuses 22, then transformer 13 is deenergized and thus the pilot circuit is no longer supplied with current through its secondary coil 15 with the result that compressor contacts are opened as by gravity or a spring 23. Thus an extremely simple arrangement has been provided for insuring complete protection of an air conditioning apparatus in case of failure of the fan motor circuit. Without this arrangement, the compressor would continue to operate upon failure of the fan circuit thus resulting in high condenser pressure with consequent danger of overloading the compressor motor. However, as long as the circuits are operative, a positive and yet simple means is afforded for insuring operation of the various refrigerating elements. A further advantage of this arrangement is that the transformer 13 can be a step-down transformer to permit a relatively low voltage in the pilot circuit with consequent safety to a user as well as lower installation costs.

In Fig. 3, the identical circuits of Fig. 2 are employed and corresponding parts are therefore given the same reference numbers. However, Fig. 3 is also arranged to control a three-phase circuit so that it has the same desirable features above mentioned. The third phase 24 of the main supply wires is connected to the compressor by wire 25. To insure adequate protection of the compressor motor in case this phase, but no other, should fail due to blowing out of a fuse 26 or other cause, I have provided improved means for shutting down the compressor and thus avoiding continued operation thereof on the remaining phase. Such continued operation would result in overload of this phase with consequent burning out of the compressor motor. To accomplish this, a relay 27 is connected to wire 25 and to one of the wires such as 28 of the fan motor circuit, preferably at a point after fuses 22. Relay coil 27 controls contacts 29 which are normally open by gravity or by a spring 30 when the apparatus is shut down. However, upon energization of the fan motor circuit by closure of switch 10, relay coil 27 will then be energized, thus closing contacts 29 to provide a closed pilot circuit.

In operation of the Fig. 3 modification, if it is assumed that fuse 28 should blow out, then there is maintained through relay coil 27 a feed-back circuit from wire 28 and thence through coil 27 across motor windings 31 and 32, wire 33 and back to wire 28. However, the voltage in this feed-back circuit is materially less than normal voltage, and hence coil 27 is not of sufficient strength to hold contacts 29 closed against the action of spring 30. It will be understood that coil 27 is designed to close contacts 29 only when the coil voltage is above feed-back voltage. When contacts 29 open, then the pilot circuit is deenergized, thus opening main contactors 18 and stopping operation of the compressor motor.

In Fig. 4, circuits are provided for a two-phase motor. The fan motor circuit and transformer 13 are identical to Figs. 2 and 3, these being supplied from one phase B. The pilot circuit is identical to that of Fig. 3 except that switch 35, corresponding to switch 29, is operated by the other phase A. A further difference over Fig. 3 is that each phase is carried through the main contactor 18, one phase being connected thereto by wires 36 and 37 to one of the compressor motor windings while the other phase is connected by wires 39 and 40 to the other phase winding of the compressor motor, the two motor windings 55 then being connected to the other side of their respective phases by wires 42 and 43. In operation, if one or the other of fuses 44 in phase A should blow out, then relay coil 45 is deenergized to permit opening of contacts 35 by gravity or by a spring 46, thereby opening the pilot circuit with consequent deenergization of solenoid 23 and opening of main contact 18. Inasmuch as contacts 18 control both phases as above described, it is seen that the compressor motor will be completely disconnected. In the event that one or the other of fuses 47 or 22 of phase B should blow out, then transformer 13 and the pilot circuit are deenergized with the result that main contacts 18 open. The overload relays 20 and their contacts 21 will normally remain closed.

A common feature between Figs. 2, 3 and 4 is that the pilot circuit in all forms is controlled by the transformer current which is taken from a single phase of the main line. The transform-

er arrangement has the further advantage of being free of contacts or mechanical links or circuit breakers with the result that the pilot circuit cannot possibly be maintained closed by sticking contacts or other mechanical contrivances. Figs. 3 and 4 have the further common feature that the pilot circuit protects the compressor motor for the phase or phases which do not supply the current to energize the pilot circuit.

In Fig. 5, I have shown a modification wherein the pilot circuit is controlled by a relay 49 placed in series in the fan motor circuit for controlling contacts 50 of the pilot circuit. In operation of this device, if any part of the fan motor circuit should fail, then coil 49 will be deenergized with the result that the pilot circuit will open. Deenergization of the pilot circuit will open the main contactors 18 of the compressor motor circuit. Hence it will be impossible for the compressor motor to operate without operation of the fan motor. The transformer controls shown in Figs. 2 to 4 are, however, preferred due to the possibility of using low voltage throughout in the pilot circuit.

From the foregoing disclosure, it is seen that I have provided an extremely simple, positive and yet highly effective means for definitely controlling the compressor motor in a manner which compels simultaneous operation of the condenser blower motor, and at the same time the pilot circuit insures complete shutdown of the compressor motor upon failure of one phase of the compressor motor system. The accomplishment of this result in a simple, economical and positive manner is highly desirable as it avoids possibility of the blower becoming inoperative while the compressor continues to operate, thus preventing the compressor from building up an excess head pressure. My improved arrangement also permits a relatively low voltage for the pilot circuit thereby affording a greater degree of safety in the installation and operation of the unit.

It will of course be understood that various changes in details of construction and arrangement of parts may be made by those skilled in the art without departing from the spirit of the invention as set forth in the appended claims.

I claim:

1. In combination, a refrigerating system having a compressor motor and motor driven means for circulating a cooling medium over a condenser, a pair of circuits one for supplying current to the compressor motor and the other for supplying current to said circulating motor, a pilot circuit adapted to open or close said compressor motor circuit, and means for controlling said pilot circuit by said circulating motor circuit, the circuits being so arranged that the circulating motor is required, before the pilot circuit is conditioned to close said compressor-motor circuit, to be fully energized and thereby compel circulation of a cooling medium over the condenser to minimize the presence of back pressure upon starting of the compressor.

2. In combination, a refrigerating system having a compressor motor and motor driven means for circulating a cooling medium over a condenser, a pair of circuits one for supplying current to the compressor motor and the other for supplying current to said circulating motor, a pilot circuit adapted when energized to open or close said compressor motor circuit, and means energized by current in the circulating motor circuit for effecting energization of said pilot

- 5 circuit, the circuits being so arranged that the circulating motor is required, before the pilot circuit is conditioned to close said compressor-motor circuit, to be fully energized and thereby compel circulation of a cooling medium over the condenser to minimize the presence of back pressure upon starting of the compressor.
- 10 3. In combination, a refrigerating system having a compressor motor and motor driven means for circulating a cooling medium over a condenser, a pair of circuits one for supplying current to the compressor motor and the other for supplying current to said circulating motor, a pilot circuit adapted to open or close said compressor motor circuit, and a transformer having its primary coil energized by said circulating motor circuit and its secondary coil connected into said pilot circuit for supplying an induced current thereto, the circuits being so arranged that the circulating motor is required, before the pilot circuit is conditioned to close said compressor-motor circuit, to be fully energized and thereby compel circulation of a cooling medium over the condenser to minimize the presence of back pressure upon starting of the compressor.
- 15 4. The combination set forth in claim 1 further characterized in that the compressor motor circuit has a solenoid operated switch whose solenoid is energized by the pilot circuit.
- 20 5. The combination set forth in claim 1 further characterized in that the compressor motor circuit has a solenoid operated switch whose solenoid is energized by the pilot circuit, an overload switch forming a part of the pilot circuit, and an overload relay in said compressor motor circuit for controlling said overload switch.
- 25 6. In combination, a refrigerating system having a multi-phase compressor motor and a motor for circulating a condenser cooling medium, a circuit for said circulating motor, a multi-phase circuit for said compressor motor, a pilot control circuit for opening and closing said compressor circuit, said pilot circuit and circulating motor circuit being so arranged that the circulating motor is required, before the pilot circuit is conditioned to close said motor-compressor circuit, to be fully energized and thereby compel circulation of a cooling medium over the condenser to minimize the presence of back pressure upon starting of the compressor, and means in said control circuit adapted automatically upon failure of any phase of the compressor circuit to open all phases thereof.
- 30 7. In combination, a refrigerating system having a multi-phase compressor motor and a motor for circulating a condenser cooling medium, a multi-phase circuit for said compressor motor, a circuit for said circulating motor, a pilot circuit for opening and closing said compressor
- 5 circuit, said pilot circuit and circulating motor circuit being so arranged that the circulating motor is required, before the pilot circuit is conditioned to close said motor-compressor circuit, to be fully energized and thereby compel circulation of a cooling medium over the condenser to minimize the presence of back pressure upon starting of the compressor, a main switch operated by said pilot circuit for controlling certain phases of said compressor motor circuit while another phase is continuously connected to the compressor motor, and means for opening said main switch automatically upon failure of said continuously connected phase.
- 10 8. In combination, a refrigerating system having a multi-phase compressor motor and a motor for circulating a condenser cooling medium, a multi-phase circuit for said compressor motor, a circuit for said circulating motor, a pilot circuit for opening and closing said compressor circuit, said pilot circuit and circulating motor circuit being so arranged that the circulating motor is required, before the pilot circuit is conditioned to close said motor-compressor circuit, to be fully energized and thereby compel circulation of a cooling medium over the condenser to minimize the presence of back pressure upon starting of the compressor, a main switch operated by said pilot circuit for controlling certain phases of said compressor motor circuit while another phase is continuously connected to the compressor motor, and means for opening said main switch automatically upon failure of said continuously connected phase.
- 15 9. In combination, a refrigerating system having a two-phase compressor motor and motor-driven means for circulating a cooling medium around a condenser, a circuit for the circulating motor, a two-phase circuit for the compressor motor, a pilot control circuit for said compressor circuit, a main switch controlling both phases of said compressor motor circuit, means energized by said control circuit for controlling said switch, means for controlling said control circuit by one of said phases, and means for also controlling said control circuit by the other of said phases whereby upon failure of either of said phases said control circuit effects opening of said main switch, said pilot circuit and circulating motor circuit being so arranged that the circulating motor is required, before the pilot circuit is conditioned to close said motor-compressor circuit, to be fully energized and thereby compel circulation of a cooling medium over the condenser to minimize the presence of back pressure upon starting of the compressor.
